UNITED STATES PATENT OFFICE.

THOMAS R. COOK, OF PITTSBURGH, PENNSYLVANIA.

DESIGN FOR A CLAMP TERMINAL-CONNECTOR FOR SECONDARY BATTERIES.

56,739.

Specification for Design.

Patented Dec. 14, 1920.

Application filed August 10, 1920. Serial No. 402,695. Term of patent 14 years.

To all whom it may concern:

Be it known that I, THOMAS R. COOK, a citizen of the United States, residing at Pittsburgh, in the county of Allegheny and State of Pennsylvania, have invented a new, original, and ornamental Design for a Clamp Terminal-Connector for Secondary Batteries, of which the following is a specification, reference being had to the accompanying drawing, forming part thereof.

In the drawing:

Figure 1 is a side plan view of the clamp

terminal connector; Fig. 2 is a top plan view thereof, and Fig. 3 is a side view.

I claim:

The ornamental design for a clamp terminal connector for secondary batteries, as shown.

THOMAS R. COOK.
